UNITED STATES PATENT OFFICE

171,545

TELEVISION PROGRAM DISPLAY STAND

Rodney A. Johnson, Salem, N. J.

Application August 3, 1953, Serial No. 26,257

Term of patent 14 years

(Cl. D1—2)

To all whom it may concern:

Be it known that I, Rodney A. Johnson, a citizen of the United States, residing at Salem, in the county of Salem and State of New Jersey, have invented a new, original, and ornamental Design for Television Program Display Stand, of which the following is a specification, reference being had to the accompanying drawing, forming part thereof.

In the drawing:

Fig. 1 is a front perspective view of a television program display stand showing my new design; Fig. 2 is a rear perspective view thereof.

I claim:

The ornamental design for a television program display stand, as shown.

RODNEY A. JOHNSON.
